APPARATUS FOR FORMING METALLIC ARTICLES

Emil Sirp, Downers Grove, and John S. Stull, Chicago, Ill., assignors to Western Electric Company, Incorporated, New York, N. Y., a corporation of New York

Application March 27, 1943, Serial No. 480,826

5 Claims.

(Cl. 82—19)

This invention relates to an apparatus for forming metallic articles.

In the manufacture of some types of vacuum tubes, the glass envelope of the tube is fixed in a funnel-shaped metallic part. Due to the difference in the coefficients of expansion of the metal part and the glass envelope, it is desirable to form the funnel-shaped portion of the metallic member with a thin enough cross section to permit it to expand and contract to the same extent as the glass. Heretofore, the forming of such parts has been exceedingly difficult due to the fact that the cross section of the part being formed is so thin that the cutting tools bend the part rather than cutting a part of the metal off of it.

It is an object of the present invention to provide an apparatus for forming irregularly shaped metallic parts of thin cross section.

In accordance with one embodiment of the invention, a substantially funnel-shaped part, having the hollow conical portion thereof provided with relatively thick walls, is rotated about the axis of the part and cutting tools diametrically opposed one to another are advanced into engagement with opposite sides of the wall of the hollow conical portion of the blank whereby, when the blank is rotated, the cutting knives will serve the double purpose of cutting a part of the metal away to form the desired thin-walled section, gradually tapering to a thicker wall as the apex of the conical portion is approached, and of acting as supports for the wall being formed. The cutting tools are advanced toward the blank and are guided by cams so that, as the cutting proceeds, the tools move apart slightly while retaining their cutting surfaces diametrically opposed with respect one to another.

A better understanding of the invention may be had by reference to the following detailed description when considered in conjunction with the accompanying drawings, wherein

Fig. 1 is a plan view of apparatus embodying the invention showing the cutting tools in their retracted, inoperative position;

Fig. 2 is a view similar to Fig. 1, except that in Fig. 2 the cutting tools are shown in an advanced position and parts of the apparatus are broken away to show more clearly the tool holders and cooperating parts;

Fig. 3 is a transverse vertical sectional view taken substantially along the line 3—3 of Fig. 2 in the direction of the arrows showing the end formation of the tools and the relative position

of the tool holders and cams which guide the tool holders;

Fig. 4 is a greatly enlarged fragmentary sectional view showing the position of the cutting tools at the beginning of the operation in dot and dash lines and the position of the cutting tools at the end of the operation in solid lines; and

Fig. 5 is a fragmentary sectional view on substantially the same scale as Fig. 4 showing a glass envelope mounted in the article formed by the present apparatus.

Referring to the drawings, wherein like reference characters designate the same parts throughout the several views, it will be seen that the part to be formed, as shown in Fig. 5, comprises a main body portion 10 having a hollow frusto-conical portion 11, into which a glass envelope 12 of a vacuum tube is to be set. It should be noted that the walls of the portion 11 of the article increase in thickness gradually from an exceedingly thin cross section at the right end thereof (Fig. 5) to the point designated 13 and that the gradual increase in thickness becomes a more rapid increase from the point designated 13 to the end of the cut, as shown at 14. The blank from which this article is to be formed is shown in Fig. 1 and may be formed to the shape as shown therein in any suitable manner preparatory to being operated upon by the apparatus shown herein. A blank which has been formed to the configuration shown in Fig. 1 may be placed in any suitable chuck 18, which may be rotated to rotate the blank about its own axis in any suitable manner while holding the blank against longitudinal movement. The chuck and other portions of the apparatus are mounted upon a bed 19, which serves to support the apparatus and may comprise the bed of any screw machine or other mechanism for imparting rotation to the chuck 18. Mounted upon the bed 19 are a pair of cams 20 and 21, which may be adjustably mounted on the bed 19 by means of machine screws 22 and 23, respectively. The cams 20 and 21 serve to guide the cutting tools, as will be described more in detail hereinafter.

Reciprocably mounted with respect to the bed 19 is a cutter carrying housing 25 having a pair of posts 26 and 27 extending upwardly from the base thereof for entering apertures 28 and 29 in tool supports 30 and 31, respectively. The aperture 28 is cylindrical and the tool support 30 is thus pivotally mounted on the post 26, whereas the aperture 29 is elongated slightly to permit longitudinal movement of the tool support

31 as well as relative movement thereof about the post 27. Fixed in the tool supports 30 and 31 are a pair of cutting tools 32 and 33, which may be held in place by means of machine screws 34—34. It should be noted that the tools are directly opposite one to the other and thus will serve to prevent each other from bending the wall being formed. The two tool supports 30 and 31 are urged to move away from each other by a compression spring 35 mounted in a pocket 36 formed in the tool support 31 and bearing against the tool support 30. The tool supports are thus urged apart and into engagement with abutment screws 37 and 38 threaded into the side walls of the housing 25 and locked in adjusted position therein by lock nuts 39 and 40. The tool supports 30 and 31 have cam rollers 41 and 41 mounted beneath them for engagement with cams 20 and 21 as the housing 25 is moved to the left (Figs. 1 and 2). In addition to carrying the roller 41 extending from its undersurface, the tool support 31 has an adjustable abutment screw 42 threaded into a post 43 depending from its undersurface. The post 43 extends through an aperture 44 formed in the bottom of the housing 25 and the post 43 may have the adjustable abutment screw 42 locked in position with respect to it by means of a lock nut 45.

Seated in the right hand wall (Figs. 1 and 2) of the housing 25 is a compression spring 46, which is set into a socket 47 and urges a cylindrical plunger 48 against the right edge (Fig. 2) of the tool support 31, thereby to hold the right hand surface of the aperture 29 against the post 27, thus tending to hold the tool 33 advanced somewhat to the left. The bed 19 of the apparatus has an abutment member 50 positioned on it which extends upwardly into the path of the abutment screw 42 and after the tools have been advanced to the position as shown in Fig. 2, the abutment screw 42 will strike the abutment member 50 and the tool support 31 will be held stationary while the housing 25 continues to advance to the left (Fig. 2), thus compressing the compression spring 46 whereby the tool 31 will stop in the position shown in full lines in Fig. 4 while the tool 32 continues to advance to the position shown in full lines in Fig. 4. It should be noted that the face of the cam 21 slopes rather steeply during the first part of the movement of the cam roller 41 across its surface and that after travelling up this slope to cut the blank up to the point 13, the slope of the cam becomes more gradual to thereby advance the tool 31 less rapidly and gradually lessen the depth of cut formed by the tool 31 and increase the thickness of the wall of the portion 11 of the blank.

A better understanding of the apparatus may be had by reference to the following brief description of the operation thereof. After a blank has been formed to the shape shown in Fig. 1 by any suitable machining or milling operations, the blank may be placed in the chuck 18 and rotated about its own axis. While the blank is being rotated, the housing 25 may be advanced in any suitable manner, for example, by operation of the manually actuatable mechanisms (not shown) to advance the tools 31 and 32 straight towards the right hand edge of the blank, as viewed in Fig. 1. As the tools advance toward the blank, the cam rollers 40 and 41 will strike the surface of the cams 20 and 21, which will move the tool holders 30 and 31 toward each other until both of the tools engage the right hand edge of the frusto-conical shaped portion

of the blank and begin the cutting operation. As soon as the cutting operation begins, the cam roller 40 will engage the receding portion of the cam 20 and while the tool carrier 31 continues to rock clockwise, being driven by its cam roller 41, the tool carrier 30 will also rock clockwise, thus to cut the portion of the blank between its right hand end and the point 13. As soon as the tools which are held diametrically opposite one to another reach the point 13 on the blank, the cam roller 41 will reach the gradually sloping portion of the cam 21 and while the tool holder 30 and tool 32 continue to move in a straight line as the cam roller 40 rolls down the surface of the cam 20, the spring 35 will urge the tools to move apart and the tapering portion between the points 13 and 14 on the blank, as shown in Fig. 5, will be formed. As soon as the tools reach the position shown in Fig. 2, continued movement to the left, of the tool carrier 31, will be stopped by the engagement of the abutment screw 42 with the abutment 50 and while the tool 32 continues to perform its cutting operation to complete the formation of the blank, the tool 31 will be held stationary. After the blank has thus been completely formed, the housing 25 may be moved back to the position shown in Fig. 1 and the operation may be repeated on a new blank.

What is claimed is:

30. 1. An apparatus for forming a substantially funnel-shaped part with the hollow frusto-conical portion's walls tapering comprising means for rotating the blank about its own axis, inner and outer cutting tools, means for resiliently urging said tools apart, means for supporting the tools for movement at angles to the axis of rotation of a part and for holding said tools in a position where they will act as supports for the wall being formed between them, and cam means for overcoming said resilient means to move the tools at different angles to the axis of rotation of the blank.
35. 2. An apparatus for forming a substantially funnel-shaped part with the hollow frusto-conical portion's walls tapering comprising means for rotating the blank about its own axis, inner and outer cutting tools, means for resiliently urging said tools apart, means for supporting said tools eccentrically of the axis of rotation of the blank, cams for guiding said tools for movement at different angles to the axis of rotation of the blank, and means for reciprocating the tools with respect to the blank.
40. 3. An apparatus for forming a substantially funnel-shaped part with the hollow frusto-conical portion's walls tapering comprising means for rotating the blank about its own axis, inner and outer cutting tools, means for resiliently urging said tools apart, means for supporting said tools eccentrically of the axis of rotation of the blank, cams for guiding said tools for movement at different angles to the axis of rotation of the blank, means for reciprocating the tools with respect to the blank, and means for stopping the reciprocation of one tool prior to the stopping of the reciprocation of the other tool.
45. 4. An apparatus for forming a substantially funnel-shaped part with the hollow frusto-conical portion's walls tapering comprising means for rotating the blank about its own axis, inner and outer cutting tools, means for resiliently urging said tools apart, means for supporting said tools eccentrically of the axis of rotation of the blank, cams for guiding said tools for movement at different angles to the axis of rotation of the blank,
50. 5. tools eccentrically of the axis of rotation of the blank, cams for guiding said tools for movement at different angles to the axis of rotation of the blank, means for reciprocating the tools with respect to the blank, and means for stopping the reciprocation of one tool prior to the stopping of the reciprocation of the other tool.
55. 6. An apparatus for forming a substantially funnel-shaped part with the hollow frusto-conical portion's walls tapering comprising means for rotating the blank about its own axis, inner and outer cutting tools, means for resiliently urging said tools apart, means for supporting said tools eccentrically of the axis of rotation of the blank, cams for guiding said tools for movement at different angles to the axis of rotation of the blank, means for reciprocating the tools with respect to the blank, and means for stopping the reciprocation of one tool prior to the stopping of the reciprocation of the other tool.
60. 7. An apparatus for forming a substantially funnel-shaped part with the hollow frusto-conical portion's walls tapering comprising means for rotating the blank about its own axis, inner and outer cutting tools, means for resiliently urging said tools apart, means for supporting said tools eccentrically of the axis of rotation of the blank, cams for guiding said tools for movement at different angles to the axis of rotation of the blank, means for reciprocating the tools with respect to the blank, and means for stopping the reciprocation of one tool prior to the stopping of the reciprocation of the other tool.
65. 8. An apparatus for forming a substantially funnel-shaped part with the hollow frusto-conical portion's walls tapering comprising means for rotating the blank about its own axis, inner and outer cutting tools, means for resiliently urging said tools apart, means for supporting said tools eccentrically of the axis of rotation of the blank, cams for guiding said tools for movement at different angles to the axis of rotation of the blank,
70. 9. means for reciprocating the tools with respect to the blank, and means for stopping the reciprocation of one tool prior to the stopping of the reciprocation of the other tool.
75. 10. An apparatus for forming a substantially funnel-shaped part with the hollow frusto-conical portion's walls tapering comprising means for rotating the blank about its own axis, inner and outer cutting tools, means for resiliently urging said tools apart, means for supporting said tools eccentrically of the axis of rotation of the blank, cams for guiding said tools for movement at different angles to the axis of rotation of the blank,

means for reciprocating the tools with respect to the blank, and means for stopping the reciprocation of one tool prior to the stopping of the reciprocation of the other tool including a movable abutment member movable with the tool, a fixed abutment member for cooperation with the movable abutment member and means for resiliently urging said tool to continue movement with the other tool.

5. An apparatus for forming a substantially funnel-shaped part with the hollow frusto-conical

portion's walls tapering comprising means for rotating the blank about its own axis, inner and outer cutting tools, means for supporting said tools eccentrically of the axis of rotation of the blank, cams for guiding said tools for movement at different angles to the axis of rotation of the blank, and means for reciprocating the tools with respect to the blank.
